CLAIM

The ornamental design for a bathtub as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the bathtub of the present invention.

FIG. 2 is a front elevation of the bathtub of FIG. 1.

FIG. 3 is a rear elevation of the bathtub of FIG. 1.

FIG. 4 is a right side elevation of the bathtub of FIG. 1.

FIG. 5 is a left side elevation of the bathtub of FIG. 1.

FIG. 6 is a top view of the bathtub of FIG. 1.

FIG. 7 is a bottom view of the bathtub of FIG. 1.

FIG. 8 is a perspective view of an alternative embodiment of the bathtub of the present invention.

FIG. 9 is a front elevation of an alternative embodiment of the bathtub of FIG. 8.

FIG. 10 is a rear elevation of an alternative embodiment of the bathtub of FIG. 8.

FIG. 11 is a right side elevation of an alternative embodiment of the bathtub of FIG. 8.

FIG. 12 is a left side elevation of an alternative embodiment of the bathtub of FIG. 8.

FIG. 13 is a top view of an alternative embodiment of the bathtub of FIG. 8; and,

FIG. 14 is a bottom view of an alternative embodiment of the bathtub of FIG. 8.
